TABLE TOP

Philip M. Friedlander, Brooklyn, N. Y., assignor to
Bertha Friedlander, New York, N. Y.

Application June 10, 1932, Serial No. 616,384

5 Claims. (Cl. 45—31)

My invention relates to an improved folding table; that is, a table the legs of which are adapted to fold up in close relation to the top in order that it may be stored away in compact form. Tables of this kind are used by card players and for many purposes where it is desired to have a small, light table for temporary use and which can be folded up and stored in compact form when not in use.

10 One object of the invention is to provide a table of the character described which will be strong and durable and which may, notwithstanding, be made at a very reasonable cost. Another object is to provide a table of this character which will be substantially firm and steady when set up for use. Another object is to provide a table of the character described, the legs of which may be quickly opened up into operative position and which may be easily moved into 20 folded position, together with convenient spring means for holding the legs folded up close to the table top and which will serve to brace the legs and hold them steadily in their extended or operative position. Another object is to simplify 25 the construction of the table top. The table top is of the covered type, that is to say, the major portion of the top of the table is covered with a pliable material such as oilcloth, felt or any of the other covering materials commonly 30 used. The top of the table is made preferably of a single piece of material such as a plain board or veneer out of which the central portion is 35 sawn, leaving an outer ring or marginal member of rectangular or other shape which is to form the marginal portion of the finished top of the table.

The central portion or interior member which is removed from the complete board is temporarily removed and the covering material is spread across it and then this inner member with the 40 covering material thereon is reinserted into position within the marginal member; or, in other words, it is returned to the position from which it was removed. The saw cut eliminates a small quantity of the material of the board when the 45 inner member is cut from the marginal member and this saw cut removes just about the correct amount of material to provide the space between the inner member and the marginal member for the pliable covering material to be passed 50 between the inner and marginal members so that the covering material may be folded back under the bottom surface of the inner member of the table top.

55 A frame built up of strips of straight or other

shaped members having mitred joints at the corners, is attached below the table top so that it covers the slot between the inner and marginal members of the table top and anchors the folded bottom edge of the covering material. This 60 frame is screwed or otherwise attached to the under side of the table top and it forms the stiffening portion of the structure and the means to which the hinged legs are attached.

The method covered by the present application 65 relates to the formation of the table top and it broadly consists of sawing an inner section from a board to form an inner member which is detachable from the outer or marginal member, covering the inner member and returning it to 70 its original position within the marginal member.

Other features and advantages will be set forth in the following detailed description of my invention.

In the drawing forming part of this application, 75

Figure 1 is a plan view of a portion of a table embodying my invention,

Figure 2 is a sectional view on the line 2—2 of Figure 1,

Figure 3 is a sectional view on the line 3—3 80 of Figure 1,

Figure 4 is a sectional view on the line 4—4 of Figure 1,

Figure 5 is a view similar to Figure 4 but with 85 the legs in folded position,

Figure 6 is an inverted plan view of the table with the legs in folded position,

Figure 7 is a sectional view taken on the line 7—7 of Figure 6, and

Figure 8 is a sectional view taken on the line 90 8—8 of Figure 6.

I will first describe the table top forming part of my invention. The top may be made of plain board or it may be made of multi-ply veneer board. The latter is preferred because there is less tendency for the top to warp and to split and it permits the top to be made from one piece of stock. As far as the present invention is concerned, the top may be made of single-ply board or multi-ply veneer.

In preparing the table top I require a board of sufficient dimensions to form the complete top of the table and this is cut in the desired shape. In the drawing I have shown the table top as of rectangular shape with the several corners rounded as at 1, although it will be apparent that it is not necessary to my invention that the corners be rounded; nor is it necessary that the table top be of rectangular shape. This board is cut to provide a removable center member or inside 100

105

110

member 2 which may be separated from the outer or marginal member. In the construction shown in the drawing the board is sawn through on the lines 3, which lines are shown as outlining a rectangle; and I have shown these lines as extending parallel with the several outer edges 4 of the full size board.

When the board is sawn through on the four rectangular lines it will be divided into two separable sections. One of these, indicated at 5, is in the form of a rectangular frame, except for the rounded corners 1 and this forms the marginal or outer member of the table top. This member is preferably of one piece of stock, so that the rectangular marginal member requires no mitred joints at the corners and therefore no seams or joints which might provide edges against which objects might strike and therefore this marginal member has a smooth, even top surface throughout.

The cutting of the board of which the top is formed along the lines 3 creates a detachable inner member 2 which in the drawing is shown square in shape and the outer edges of this member will conform with the inner edges of the marginal member 5 and its dimensions will correspond with the inner dimensions of the marginal member except for the material which is removed by the saw in making the cut. The part which is removed by the saw cut forms a space substantially the thickness of the saw which will usually be a fraction of an inch.

The section 2 which is thus removed from the complete board is then covered with the top or covering fabric usually employed on tables of this character. I have shown a sheet of covering material 6 which may be oilcloth, leather, or any other type of fabric, and it is preferred to use a sheet of padding 7 underlying the covering material in accordance with common practice. This under lining 7 is applied to the top surface of the member 2 and the sheet of covering material is then placed over the lining material and is smoothed out so that it completely and smoothly covers the top surface of the member 2.

This covering material is of sufficient size to entirely cover the top surface of the member 2 and of such additional proportions that the four edges may be turned down against the several outer edges of the member 2 and thence folded under the under surface of this member, as indicated at 8. When the covering material has thus been applied to the member 2 the latter, with the covering material, is inserted into the rectangular opening in the marginal member 5 from which the inner member was originally severed by the saw cuts, so that the inner member seats within the opening 9 of the marginal member with the turned down portions of the covering material extending through the slots 10 between the inner top member and the marginal top member as shown in Figures 3, 4 and 5 of the drawing.

The frame or under structure may now be applied to the under side of the complete top and be secured thereto. The frame, as shown in the drawing, preferably consists of the four strips 11 which are shown as made of wood, although any other material may be employed; and the major portions of these strips are of L shape in cross section, as shown in Figure 7, having two webs 12, 13 angularly disposed, the web 13 being adapted to lie flat against the under side of the table top with the web 13 extending at right angles thereto and serving to stiffen the strip. These four strips

are connected together into a rectangular frame and they are connected to each other by mitred joints 14 at the four corners of the rectangle. The rectangular frame formed of these strips 11 is of such proportions that when the frame is placed against the under side of the table top the first webs 12 of the several strips will extend across the joint between the meeting edges of the inner top member 2 and the marginal top member 5 as clearly shown in Figure 7.

These strips will therefore rest against and grip the portion 8 of the covering material which extends through the slots 10 between the inner and outer top members and which is turned inwardly against the under surface of the member 2 as shown in Figure 7. Screws or other attaching members 15 are passed through the web 12 of the several strips or bars 11 and into the material of both the marginal member 5 and the inner member 2 of the top to firmly secure both members of the top to the frame. When the frame is thus attached to the top it serves to stiffen the latter as well as to firmly secure the inner and marginal members of the top together and also to clamp the covering material to hold the latter from being displaced.

Preferably, the strips or bars 11 are cut so that the corners which are joined to each other are of the full depth or thickness of the stock from which they are made, as indicated at 16 in the drawing. These corner portions of the frame are cut out to form rectangular recesses 17 as shown in Figure 6, to receive one end of each of the foldable legs so that each leg is pivotally mounted with one end swinging in the rectangular recesses 17 of the frame. At each corner of the frame there is a hinge member or bar 18 which passes through a lateral aperture in one end of each leg, and the hinge member extends laterally beyond the leg and projects into corresponding apertures 19 in the adjacent portions of the bars 11. It will be apparent that the legs and their hinge members are assembled at the same time the mitred joints 14 are made between adjacent or connecting bars 11 in order to permit the hinge member to be assembled in the apertures 19.

The several legs are arranged to hinge from the several corners of the frame in the manner shown in Figure 6. The several legs 20, 21, 22, 23 are shown as formed of flat stock, although they may be round or any other shape.

In the drawing they are shown tapered in width and are slightly offset in their angular positions so that the two legs which are diagonally opposite each other, such as the legs 20, 21 in Figure 6, may be folded up parallel with the under side of the table top to lie in a common plane. The other and diagonally opposite legs 22, 23 are so positioned that they may be folded into a common plane which plane is just under the plane occupied by the legs 20, 21. This permits the legs to be folded in compact shape, notwithstanding that there are four legs crossing each other adjacent the center of the table.

Each leg is provided with a slot 24 cut therethrough and extending lengthwise of the leg and preferably in the middle thereof. There is a spring member 25 having one end secured by the screws 26 or other means to the under side of the inner top member 2; and these spring arms are bent to extend as shown at 27 through the aperture 24 of each leg and the free end of each spring member is shown as turned or bent at 28 and this bent end is provided with an

aperture 29. The spring arms are of sufficient length to cause them as shown in Figure 6, to pass through the slots 24 of the legs and to extend across the hinged end of the leg. These 5 arms are preferably made of spring metal and are so designed that when the legs are in the folded position shown in Figure 6, the portions of the arms which emerge from the slots 24 of the legs press against the under sides of the 10 legs to press the latter toward the bottom of the table top. The legs 20, 21 will therefore be held against the under side of the table top and the legs 22, 23 will be held pressed against the legs 20, 21. When in this condition the table may 15 be carried about with the legs snugly held by the several spring arms to prevent rattling and prevent the legs from unfolding.

At the bottom edge of each opening 24 of the legs I have shown a pin 30 projecting in the 20 direction of the leg and this pin is adapted to engage in the aperture 29 of the spring arm when the legs are in extended or open position.

Assuming that the table is in the folded position shown in Figure 6, all that is necessary to 25 open or extend the table for use is to first swing the legs downwardly to positions at right angles to the table top; and during this movement the bottom edges 31 of the slots 24 in the legs press downwardly on the spring arms, increasing their 30 tension, and when the legs are perpendicular to the table top, the pins 29 will enter the apertures 30 of the spring arms. The spring arms are then locked to the table legs and hold the latter rigidly in the manner of a bracket or brace, so that 35 the legs remain perpendicular to the table top. The operator need give no attention to the locking of the pins 29 in the apertures 30 because this takes place automatically when the leg is in the lower position.

40 When all four legs have been moved into operative position, they are firmly and rigidly held. The hinge pins 18 secure one end of each leg to the frame and the side edges of the rectangular openings 17 of the frame prevent lateral 45 sway of the legs whereas the spring arms engaging the pins 29 prevent the legs from swinging on their hinges while so locked.

To fold up the table after use, the operator 50 merely presses on the projecting ends 28 of the several spring arms sufficiently to disengage them from the pins 29 at the same time swinging the legs radially inwardly. When the legs have been 55 swung partly inwardly the spring arms, pressing against the outer sides of the several legs, will cause them to fold up under the table top, as shown in Figure 6.

From the above it will be apparent that I have 60 provided a foldable table of substantial construction which may nevertheless be made at relatively low manufacturing cost. As the table top is made of one piece of stock it is unnecessary to mitre any portion of it. The operation 65 of sawing out the board from which the inner and marginal top members are formed is a very quick operation and requires no special machinery as this may be done with an ordinary circular saw. By avoiding mitred corners in the table top there are no rough edges and the top 70 as a whole is therefore smoother than one built up of mitred pieces. The saw which cuts out the board of which the top is made removes the right quantity of material to leave a crack be-

tween the inner and outer top members just suitable for the covering material to pass therethrough so that when the inner member with the covering material are inserted into the opening of the marginal member the parts fit snugly 80 together. The frame members overlying the joint between the inner and outer top members maintains the latter in proper alignment and also secures them firmly to the frame to preserve the alignment of the top. In the full combination of my invention the frame also serves to clamp the under edges of the covering material the same time that the frame is attached to the under side of the top.

Having described my invention, what I claim 90 is:

1. A table including a top composed of an annular marginal member, an inner member and a covering on said inner member, said inner member and its cover being inserted into the inner space in said annular member, said covering materially being turned back on the under side of said top, a frame attached to the under side of said table top, said frame extending across the meeting line of said inner and outer 100 table members and engaging against both said table members and clamping the turned under portion of said covering material, said frame being secured to said top.

2. A table including a top composed of an annular marginal member, an inner member, said inner member being inserted in the inner space in said annular member, a frame for the under side of said table top, said frame extending across the meeting line of said inner and outer 110 table members and engaging against both said table members and, means for securing said frame to both said top members.

3. In a table including a top composed of a jointless, annular marginal member, an inner 115 member, a covering material on said inner member, said inner member and its cover being inserted into the inner space in said annular member whereby the covering material is engaged between the outer edges of the inner member and 120 the inner edges of the annular member and a frame attached to said annular and said inner top members.

4. A table including a top composed of a rectangular, annular, marginal member, an inner 125 member conforming to the shape of the opening in said annular member, a covering on said inner member, said inner member and its covering being inserted into the space in said annular member, said covering material being 130 turned back on the under side of said top, a rectangular frame attached to the under side of said table top and covering extending across the meeting lines of said inner and outer top 135 members and engaging against both said table members and, means for securing said frame to both top members.

5. The method of making covered table tops which consists of sawing a single board to remove an inner member and to provide a jointless, annular, marginal member covering said inner top member and replacing said inner top member with its covering material into the opening in said marginal member with the covering material extending through the crack between 145 said inner and outer top members.

PHILIP M. FRIEDLANDER.
